HEAT TREATING APPARATUS

Lloyd W. Young, Scotch Plains, N. J., assignor to
 The Linde Air Products Company, a corporation
 of Ohio

Application May 1, 1940, Serial No. 332,680

12 Claims. (Cl. 266—4)

This invention relates to the heat treatment of elongated metal bodies having longitudinally spaced cylindrical and/or laterally extending surface portions, and, more particularly, to apparatus for heat treating and hardening in succession the surfaces of a plurality of cams and bearings upon a camshaft by the application of localized high temperature heat, such as that provided by an oxy-acetylene flame.

Camshafts vary widely in physical dimensions, such as overall length, distance between cams, distance between cams and bearings, cam and bearing widths, cam contours, and other dimensions. Consequently, apparatus for hardening cams and bearings on a camshaft, to be successful, must necessarily be so constructed that the least possible time will be required to align a cam or bearing being treated with the heating means, or to make adjustment for cam spacing and other variables.

The objects of this invention are to provide apparatus for heat treating a plurality of spaced and/or laterally extending portions of a metal body; to provide apparatus for hardening a cam or a plurality of cams on a camshaft in which each cam is hardened individually, but in which the results of hardening each cam are uniformly duplicated in the case of all the cams; to provide such apparatus by which the bearings as well as the cams on a camshaft can be hardened without shifting the camshaft or making unnecessary adjustments to the apparatus; to provide such apparatus which is easily adjustable so as to permit treatment of camshafts of varying lengths, and cams and bearings of different widths; to provide such apparatus in which a relative reciprocal motion between a cam being treated and a source of high temperature heat is produced; to provide such apparatus in which the camshaft may be rotated while a bearing is being treated; to provide such apparatus in which high temperature heating flames are directed from a blowpipe against the surface portions to be hardened and in which the blowpipe may be moved away from the portion being treated and simultaneously therewith the supply of gases to the blowpipe automatically turned off; to provide such apparatus in which each individual cam may easily be registered in operative relation with respect to the heating means; and, generally, to provide such apparatus which will be simple in construction and economical in operation.

Other objects and novel features of this invention will become apparent from the following

description and accompanying drawings, in which:

Fig. 1 is a front elevation of apparatus, constructed in accordance with this invention, for hardening a plurality of cams and bearing areas upon a camshaft.

Fig. 2 is a vertical end view of the apparatus of Fig. 1;

Fig. 3 is a vertical sectional view of the apparatus of Fig. 1, taken along line 3—3 of Fig. 1;

Fig. 4 is a partial vertical sectional view of the apparatus of Fig. 1, taken along line 4—4 of Fig. 1;

Fig. 5 is a partial vertical sectional view taken along line 5—5 of Fig. 1 showing in clearer detail the heating means and an indexing device used in treating cams;

Fig. 6 is a partial vertical sectional view taken along line 6—6 of Fig. 1, showing in clearer detail the mechanism for rotating the camshaft while a bearing is being treated;

Fig. 7 is a partial vertical sectional view, similar to Fig. 5, illustrating the operation of the indexing device in aligning a cam with the heating means;

Fig. 8 is a fragmentary end view illustrating the manner in which the quenching medium is turned off and on; and

Fig. 9 is a top view of the heating and quenching means and a cam being treated, as illustrated in Fig. 8.

In general, as in Figs. 1 and 2, apparatus constructed in accordance with this invention may comprise a framework F supporting, in a horizontal position, a camshaft A having laterally extending cams C and cylindrical bearings B thereon. Heating means H and quenching means Q are carried by a support or carriage U, which rolls along a tubular shaft T. Heating means H

is adapted to direct high temperature heating flames, preferably formed by a combustible mixture of oxygen and acetylene, against the oppositely disposed and laterally extending surfaces of a cam C, or against the surface of a bearing B. Quenching means Q is adapted to direct a stream of quenching fluid, such as water, against the apex of a heated cam or against the heated surface of a bearing to harden the same.

During heating, a rod R, reciprocated by power means such as a motor M, and provided with adjustable stops S which engage support U when in heating position, causes support U to reciprocate through a suitable distance so that the heating flames will move from one side of the cam or bearing to the other, and the surface

thereof will be quickly heated to a temperature at or above the critical range. To discontinue heating, support U is moved away from the heating position, causing tube T to turn and thereby close a valve V controlling the flow of gases which produce the heating flames. At the same time, as in Fig. 2, tube T, in turning, will turn on a valve V' which controls the supply of quenching fluid to quenching means Q, thereby causing the quenching medium to be directed against the heated surface of the cam or bearing. When the support U is moved further away from the cam-shaft, such as to the dotted position of Fig. 2, the quenching medium will also be turned off, and the support U may then be moved to the next 15 cam or bearing to be treated.

With the support U positioned in front of a cam to be treated, an indexing device I is moved inwardly toward the cam-shaft in positioning the cam radially with respect to the heating and 20 quenching means, the cam-shaft being turned manually through a sufficient angle so that the laterally extending portion of the cam will engage the indexing device.

During heating of both cams and bearings, support S is reciprocated, but during heating of bearings, the cam-shaft itself is rotated. Gearing G, which is driven by motor M, may be disconnected at will or thrown in to rotate the cam-shaft when a bearing is being treated. During 30 rotation, high temperature heating flames are directed against the bearing and the surface thereof is quickly heated to the desired temperature. After heating, support U is moved outwardly away from the cam-shaft to turn off the heating gases and turn on the quenching medium; and, after the quenching period, the support is moved further away to turn off the quenching medium, as in treating cams.

From the foregoing general description, the principles of operation of the apparatus will be apparent, and the more detailed description which follows will clarify the details of operation of the various parts involved.

Referring again to Fig. 1, the framework F comprises a bed 10, which may be an I-beam, and to one end of which an upright fixed post 11 is secured in any suitable manner, such as by welding. At the upper end of fixed post 11 is a suitable bushing 12 for a drive shaft 13 connected with gearing G. At the inner end of drive shaft 13 is a fixed center 14 which is inserted in the center hole of the cam-shaft, and disposed radially outward therefrom is a driving pin 15 which is inserted in the indexing hole of the cam-shaft to rotate the cam-shaft while a bearing is being treated. At the opposite end of bed 10 is a movable upright post 16 which, as in Fig. 3, is secured to the top of the bed or I-beam 10 by a screw clamp having a handle 17. Movable post 16 may be moved to different positions along the top of the bed of the framework to accommodate cam-shafts of different lengths. As in Figs. 1 and 3, post 16 is provided at its upper end with a movable center 18, which engages the center hole in the opposite end of the cam-shaft. Center 18 may be moved toward or away from the cam-shaft by a handle 19, and is utilized in placing an untreated cam-shaft in the apparatus, or removing a treated cam-shaft therefrom.

The support or carriage U, as in Figs. 1 and 4, is provided with two pairs of beveled or V-shaped rollers 21 journaled on stub shafts 22, which are secured in ears 23 extending forwardly and rearwardly from the central portion of support U.

The central portion of support U, i. e. central with respect to the distribution of weight, is provided with a suitable aperture through which tube T passes, and the inner surface of each pair of rollers engages the side of a key or tongue 24. Key or tongue 24 is preferably formed integrally with the tube T on the upper side thereof, so that when support U is moved toward or away from the cam-shaft, tube T will be caused to turn or pivot. One end of tube T is journaled in a bearing 25 secured to fixed post 11, key 24 extending to within a short distance of bearing 25. The opposite end of tube T is journaled in a bearing 26 secured to, or formed integrally with, movable post 16. To permit movement of post 16 along bed 10, a bushing or sleeve 27, as in Fig. 3, is interposed between tube T in bearing 26, the bushing having a groove in which tongue 24 slides when post 16 is moved longitudinally.

The upper portion of support U comprises a supporting arm 28, which, as in Fig. 2, extends upwardly at an angle of about 30° and away from the relative location of the cam-shaft. Heating means H and quenching means Q are secured to the upper end of arm 28, while the indexing device I is pivoted on a pin 30 secured to arm 28 substantially midway thereof. The lower portion of support U comprises a weight or mass 31, which is disposed beneath the tube T and which counterbalances the weight of the heating and quenching means and the indexing device, so that little effort is required to move the support and the heating and quenching means toward or away from the cam-shaft.

Secured to arm 28, or formed integrally therewith, is a fork 32 which is adapted to engage one of adjustable stops S when the support U is in the position of Figs. 2 or 5. The rod R reciprocates in bearings 33, secured to or formed integrally with the posts 11 and 16, as in Fig. 1.

The heating means H, as in Figs. 1 and 5, comprises a blow pipe having a body 35 secured to the upper end of arm 28 by a clamp 36, which is pivotally adjustable through a bolt 37. A suitable mixer for forming a combustible mixture of gases, such as oxygen and acetylene, is installed within the body of the blowpipe, and tubes 38 lead the combustible mixture to heads 39 from which heating flames 40 are directed against the two opposite surfaces of the laterally extending portion of a cam C. Each head is provided with suitable outlets for directing a plurality of heating flames, or several relatively wide heating flames, against these surfaces, but, as in Fig. 5, heat is not applied directly to the apex or extreme point 41 of each extending portion, each apex thus being heated chiefly by conduction. The plurality of heating flames, or the relatively wide heating flames, preferably cover a lateral distance substantially equal to or slightly less than the least width of cam to be treated, the heads being reciprocated during heating so that the heating flames will traverse substantially the entire width of the cam. However, due to a tendency for the lateral edges 42 of the extending portion (see Fig. 9) to become overheated, the reciprocation is preferably terminated at points spaced from these edges. Due to the termination of reciprocatory movement at points spaced from the lateral edges, these edges as well as the apex, will be heated chiefly by conduction.

Tubes 38 are preferably relatively inflexible, so that they will support heating heads 39 in proper position, but it will be apparent that a suitable bracket secured to body 35 or clamp 36

may be provided to support heads 39 so that the heads will be adjustable easily toward or away from one another. In such a case, tubes 38 are preferably made of flexible material.

A suitable pilot burner (not shown) which burns constantly may be employed, so that as soon as the heating gases are turned on, the heating flames will be lighted instantly; or, a suitable lighting torch may be employed which is merely passed along the heads when it is desired to light the heating flames. The pilot burner or lighting torch is preferably supplied with a mixture of acetylene and air, or city gas and air, which can burn continuously at little expense.

The quenching device Q, as in Figs. 8 and 9, 15 comprises a head 43 supported between heating heads 39 by a quenching medium supply tube 44, in turn secured to blowpipe clamp 36 by an auxiliary clamp 45. Quenching head 43 is disposed at an angle with respect to heating heads 39 so that, as in Fig. 8, a jet J of quenching medium, normally water, will be directed against the point or apex 41 of the heated cam when support U is moved a slight distance backwardly and to the position of Figs. 8 and 9. As support U moves to this position, the quenching medium is turned on, in a manner to be explained later. The quenching head is preferably provided with a slotted orifice, so that a solid stream of water will impinge upon the point or apex and spread evenly along each side of the laterally extending portion of the cam. In addition, quenching head 43 and also the slot therein are considerably wider, or extend laterally for a greater distance, than heating heads 39, so that reciprocation of support U is unnecessary during quenching. The width of the stream of water or quenching fluid discharged by the quenching head is preferably as great as, or greater than, the greatest width of cam or bearing surface to be cooled.

The indexing device I, as in Figs. 5 and 7, comprises an arm 47 pivoted at its lower end on pin 30 and provided at its upper end with an indexing plate 48, secured thereto or formed integrally therewith. Plate 48 is adapted to engage the extending portion of a cam to position the same accurately for heating and quenching when support U is withdrawn the full distance from the camshaft, as in Fig. 7. When in this position, fork 32 will not engage any of the stops S. By means of a handle 49 (see Fig. 1) attached to indexing arm 47, the indexing plate 48 may be moved inwardly and into engagement with the particular cam to be treated, the camshaft being rotated slightly, if necessary, to align the extending portion of the cam radially with the indexing plate. The indexing device is mounted at the side of the heating and quenching means, and the support U is moved a short distance to the left or right, as the case may be, after the particular cam to be treated is indexed, to place the heating and quenching means in proper position so that fork 32 will engage the proper stop S. The indexing device is also moved back to its normal position of rest, where it will be held by gravity during the hardening treatment, and the support U is then moved forwardly toward the camshaft. This moves heating heads 39 into operative position with respect to the cam to be treated, causes fork 32 to engage the proper stop S for reciprocation during heating, and also causes the heating gases to be turned on automatically.

For turning on the heating gases automatically, an arm 50 provided with a split ring 51 at 75

one end, as in Fig. 2, is clamped by means of a bolt 52 to the extreme end of tube T, beyond fixed post 11. Since tube T turns when support U is moved toward the camshaft, arm 50 will also turn, and adjustable pins or bolts 53 will depress buttons 54 of valve V, thus turning on the heating gases. As in Fig. 1, the heating gases, preferably oxygen and acetylene, are supplied to valve V by inlet hoses 55, while outlet hoses 56 carry oxygen and acetylene to blowpipe body 35.

When the surface of the cam being treated has been heated to the desired temperature, the support or carriage U is moved backwardly away from the camshaft, from the full toward the dotted position of Fig. 2. As arm 50 rises, the heating gases will be turned off. In addition, the quenching medium will be turned on automatically. For this purpose, as in Fig. 2, arm 50 is provided with a pivoted link 58 having at its outer end a roller 59. When the support U is moved forwardly, link 58 will pivot upwardly as arm 50 passes downwardly, roller 59 passing over plunger 60 without turning on the quenching medium. When the support U is moved backwardly to the position of Fig. 8, i. e. substantially intermediate the full and dotted positions of Fig. 2, roller 59 will depress plunger 60 of valve V', thus turning on the quenching medium. The quenching medium, preferably water, flows from an inlet pipe 61 through valve V' and an outlet pipe 62, and thence through a suitable hose (not shown) to tube 44 and quenching head 43.

As soon as the heated cam surface has cooled sufficiently, support U is moved back to the dotted position of Fig. 2, so that the quenching medium will be turned off.

When support U is moved back to the dotted position of Fig. 2, arm 50 will contact stop 63, which is bolted to, and is adjustable vertically on, 40 the side of fixed support 11, as in Figs. 1 and 2. This will insure that support U has been moved back the exact distance necessary for proper use of indexing device I.

Referring now to Fig. 1, motor M is mounted 45 on a bracket 65 secured to, or formed integrally with, fixed post 11 and is provided with a speed reducer 66 which turns a shaft 67 at a relatively slow speed. For reciprocating rod R during the heating operation, a plate cam 68 is mounted on 50 the free or outboard end of shaft 67. The periphery of plate cam 68 has a suitable eccentric shape so that, as it rotates, a reciprocal motion will be imparted to the longer arm of a bell crank 69 which is pivoted on a pin 70 secured to post 11. This longer arm of bell crank 69 is provided 55 with a follower or roller 71, which follows the periphery of plate cam 68 during rotation of the latter. The shorter arm of bell crank 69, which is disposed substantially at right angles to the longer arm, comprises a fork 72 which engages a driving pin 73, formed integrally with and extending from the side of a clamp 74 secured to rod R. As plate cam 68 rotates, the reciprocating motion of bell crank 69 will be imparted to rod R, and thence to carriage U, through one of 60 adjustable stops S and fork 32.

The procedure involved in treating a bearing is substantially the same as that involved in treating a cam, except that no indexing is required for alignment, and the entire camshaft is rotated relatively rapidly during treatment of a bearing, whereas the camshaft remains stationary during the treatment of the extending portion of a cam. Carriage U may be reciprocated manually to apply the heating flames to

the entire surface of the bearing, or an adjustable stop S may be disposed at the correct position for reciprocating support U, as in treating cams.

To rotate the camshaft during treatment of a bearing, gearing G is utilized. As in Figs. 1 and 6, gearing G includes a spur gear 15 keyed to shaft 67 between speed reducer 66 and plate cam 68, and a gear 16 keyed to the outer end of drive shaft 13. A pinion 17, in mesh with spur gear 15 at all times, is adapted to be moved into engagement with gear 16 by upward movement of a handle 18 extending from a double mounting bracket 19. Bracket 19 is pivoted on shaft 67, and pinion 17 is mounted between the legs of bracket 19 on a pin 80 passing through and secured to the upper ends of the two legs of bracket 19.

To insure that pinion 17 will remain in mesh with gear 16 when handle 18 is moved upwardly, and also to insure that pinion 17 will not mesh with gear 16 when a cam is being treated, the lower end of bracket 19 is provided with a toggle mechanism. This toggle mechanism comprises a rod 81 having a fork 82 at its lower end, and pivoted at its upper end between the two legs of bracket 19 on a pin 83, which is secured to the lower end of each leg of the bracket. Fork 82 engages, but bears rather lightly against, the sides of rod R. A spring 84, surrounding fork 82, bears at its lower end against a washer 85 which engages rod R, and at its upper end against a washer 85 which engages bracket 19.

A stop 81, as in Fig. 6, secured to the housing of speed reducer 66 and extending laterally therefrom at a position just behind the lower end of bracket 19, is contacted by the lower end of bracket 19 and prevents further outward movement of pinion 17 when the pinion is moved out of engagement with gear 16. Movement of bracket 19 in the opposite direction is limited by engagement of pinion 17 and gear 16. Spring 84 acts to hold bracket 19 and pinion 17 in the position in which pinion 17 meshes with gear 16, or in the position in which pinion 17 is completely out of engagement with gear 16 with the lower end of bracket 19 in contact with stop 81, since for either of the two positions, the distance between rod R and pin 83 is greater than for any intermediate position. In addition, spring 84 tends to give a snap action to movement of bracket 19 in either direction past the point at which rod R, shaft 67, and pin 83 are in alignment.

The various steps in the hardening of cams and bearings on a camshaft by the apparatus just described may proceed substantially as follows:

Assume that a suitable indexing plate 48, conforming in shape to the contour of the cams to be treated, suitable heating heads 39, a suitable quenching head 43, as well as a plate cam 68 having a periphery suitable in shape for effecting the desired amplitude of reciprocation, have all been provided. The camshaft to be treated is loaded in the apparatus by moving adjustable support 16 along bed 10 a sufficient distance to accommodate the camshaft, placing the camshaft with fixed center 14 in the center hole and driving pin 15 in the indexing hole in one end of the camshaft, and moving center 18 into engagement with the center hole in the opposite end of the camshaft. Movable center 18 is tightened just enough so that the camshaft will remain in any particular radial position, but can be turned eas-

ily. Stops S are clamped on rod R, at suitable positions corresponding to the longitudinal positions of the cams C and, if desired, also corresponding to the longitudinal positions of bearings B. The position of heating heads 39 and quenching head 43 is adjusted, and the proportions of the heating gases forming the combustible mixture are regulated so that the heating flames will burn properly.

The movable support U is moved to the proper longitudinal position for treating the first surface portion to be hardened, such as a bearing B. In treating a bearing, the indexing device I is not used, but handle 18 is thrown upwardly so that pinion 17 meshes with gear 16, and motor M started so that the camshaft is rotated relatively rapidly, such as between 25 R. P. M. for relatively large bearings and 250 R. P. M. for relatively small bearings. After the pilot light or lighting burner has been lighted, the support U is moved forwardly, causing arm 58 to move downwardly and the heating gases to be turned on by pins 53 striking buttons 54 of valve V. The heating flames are then lighted, and the surface of the rotating bearing heated. The support U may be reciprocated manually during such heating, or by motor M, acting through a stop S on rod R.

After a predetermined time interval of heating, i. e. when the entire surface portion to be hardened has reached a temperature at or above the critical range, support U is moved backwardly until roller 59 depresses plunger 60 of valve V', thus turning on the quenching water. A jet J of quenching medium, normally water, is thus directed against the heated surface of the bearing, which is still rotating. When the heated surface has been cooled sufficiently, the support U is moved further backwardly until arm 58 strikes stop 83, the quenching water being shut off during such movement. In case the next surface portion to be hardened is that of a cam C, motor M is stopped, and handle 18 pulled downwardly to disengage pinion 17 from gear 16.

The support U is then moved to the proper longitudinal position for the cam to be treated, the support remaining, however, in the rearward dotted position of Fig. 2. The indexing device is next brought forward and the camshaft turned so that the extending portion of the cam is in the proper radial position for heating. The support U is then moved forwardly until fork 32 engages the stop S set for the particular cam, and motor M is started. The support U is then moved further forwardly and into heating position, with heads 39 properly positioned with respect to the stationary cam, the heating gases being automatically turned on and the heating flames lighted, as before.

After another predetermined time interval of heating, i. e. when the surface of the laterally extending portion of the cam has reached a temperature at or above the critical range, the support U is moved backwardly until roller 59 depresses plunger 60 of valve V'. As before, the heating gases will be turned off, and a jet J of quenching medium or water will be directed against the point or apex 41 of the cam C, spreading evenly over the two sides of the laterally extending portion, as in Fig. 8. When the heated surface has been cooled sufficiently, the support is again moved further backwardly, until arm 58 contacts stop 83, the quenching water being turned off during such movement. The motor M is then stopped and the support U moved to the

next position, such as the next cam to be treated, and the above operation repeated.

In the foregoing manner, all of the cams and bearings upon a camshaft can be treated quickly and expeditiously. For example, a bearing $1\frac{1}{4}$ inches in diameter and 1 inch in width, may normally require approximately 15 to 25 seconds for heating, and about 15 to 25 seconds for quenching. Again, the laterally extending portion of a cam 1 inch wide, having a normal diameter of $1\frac{1}{2}$ inches with the point or apex extending $\frac{1}{2}$ inch further outwardly, may normally require about 10 seconds for heating, and also about 10 seconds for quenching. Heating heads, particularly adapted to be used in treating such bearings and cams, will normally consume about 50 to 60 cubic feet per hour of oxygen and acetylene, each.

After all of the cams and bearings on the cam-shaft have been treated, movable center 18 is retracted and the treated camshaft removed from the apparatus. The next camshaft to be treated is placed in the apparatus in the same manner as the previous camshaft, and the treatment thereof proceeds as just described. When a plurality of identical camshafts are being treated, no adjustment of the apparatus is necessary after the various parts are once properly positioned. However, in case there is a difference in cam width or cam contour, it is necessary only to change indexing device I and cam plate 68, and adjust stops S. Heating heads 39 and quenching head 43 will be found to be suitable for a considerable variety of camshafts. If it is desired to harden a greater area of each cam, heating heads 39 may more nearly encircle the cam, but the principle of heating the lateral edges as well as the point or apex of the laterally extending portion chiefly by conduction, is utilized as before.

From the foregoing, it will be apparent that this invention provides a relatively simple and inexpensive apparatus by which results can be uniformly duplicated in the treatment of a plurality of longitudinally spaced portions of elongated ferrous metal bodies, both laterally extending portions as well as cylindrical portions. Although the treatment of cams and bearings upon a camshaft has been described with particularity, it will be understood that the apparatus is suitable for use in the treatment of other metal objects, and that various changes in the apparatus may be made without departing from the spirit and scope of this invention.

What is claimed is:

1. Apparatus for heat treating in succession, a plurality of spaced surface portions of an elongated metal body comprising, in combination, means for supporting said body; means for applying high temperature heat to such surface portions, said heating means being adapted normally to heat at any instant only a longitudinal part of such surface portions; a movable carriage for supporting said heating means; means for engaging said carriage to position said heating means longitudinally of said body in positions corresponding to each of such surface portions to be treated; and means for imparting a reciprocal motion to said carriage engaging means so as to reciprocate said heating means longitudinally of said body.

2. Apparatus for heat treating in succession a plurality of longitudinally spaced surface portions of an elongated metal body, said surface portions extending laterally from said body at different circumferential points, such apparatus comprising, in combination, means for applying

high temperature heat to such surface portions; a movable carriage for supporting said heating means, said carriage being movable longitudinally with respect to said body and also movable toward and away from said body; and means pivoted on said carriage for registering such laterally extending portions of said body circumferentially of said body when said carriage is moved to a predetermined position away from said body, so that a registered portion will be in operative relation with respect to said heating means when said carriage is moved to another predetermined position closer to said body.

3. Apparatus for heat treating in succession a plurality of spaced surface portions of an elongated metal body, said surface portions extending laterally from said body at different circumferential points, such apparatus comprising, in combination, means for supporting said body; means for applying high temperature heat to such surface portions, said heating means being adapted normally to heat at any instant only a longitudinal part of such surface portions; a movable carriage for supporting said heating means; means for registering such laterally extending portions of said body circumferentially of said body and in operative relation with respect to said heating means; means for engaging said carriage to position said heating means longitudinally of said body in positions corresponding to each of such surface portions to be treated; and means for imparting a reciprocal motion to said carriage engaging means so as to reciprocate said heating means longitudinally of said body.

4. Apparatus for heat treating in succession a plurality of spaced surface portions of an elongated metal body, a number of said surface portions extending laterally from said body at different circumferential points and other of said surface portions being cylindrical, such apparatus comprising, in combination, means for supporting said body; means for applying high temperature heat to such surface portions; means for positioning said heating means longitudinally of said body in positions corresponding to each of such surface portions to be treated, said last-named means comprising stops positioned corresponding to such surface portions to be treated; power means; means adapted to rotate said body; and means for selectively connecting and disconnecting said power means to said rotating means whereby said body may be rotated while a cylindrical surface portion is being heated and will not be rotated when a laterally extending portion is being heated.

5. Apparatus for heat treating in succession a plurality of spaced surface portions of an elongated metal body, a number of said surface portions extending laterally from said body at different circumferential points and others of said surface portions being cylindrical, such apparatus comprising, in combination, means for supporting said body; means for applying high temperature heat to such surface portions; means for positioning said heating means longitudinally of said body in positions corresponding to each of such surface portions to be treated; power means; means adapted to rotate said body; means for selectively connecting said power means to said rotating means whereby said body may be rotated while a cylindrical surface portion is being heated; and means for registering such laterally extending portions of said body circumferentially of said body in operative position with respect to said heating means.

6. Apparatus for heat treating in succession a plurality of spaced surface portions of an elongated metal body comprising, in combination, means for supporting said body; means for applying high temperature heat to such surface portions; a support for said heating means comprising a carriage mounted upon and movable along a pivoted member, said carriage and said pivoted member being so constructed and arranged that said heating means is movable toward and away from said body and said pivoted member is caused to turn by movement of said carriage toward and away from said body; means for controlling the operation of said heating means; and means associated with said control means and pivoted member and so constructed and arranged that heating is discontinued upon movement of said carriage and said heating means away from a surface portion under treatment.

7. Apparatus for heat treating in succession a plurality of spaced surface portions of an elongated body comprising, in combination, means for supporting said body; means for applying high temperature heat to such surface portions; a support for said heating means comprising a carriage mounted upon and movable along a pivoted member, said carriage and said pivoted member being so constructed and arranged that said heating means is movable toward and away from said body and said pivoted member is caused to turn by movement of said carriage toward and away from said body; means for directing a quenching medium against a heated surface portion; means for controlling the operation of said heating means; means for controlling the flow of quenching medium; and means associated with each of said control means and said pivoted member and so constructed and arranged that heating is discontinued and the quenching medium is turned on upon movement of said carriage and said heating means away from a surface portion under treatment.

8. Apparatus for heat treating in succession a plurality of spaced surface portions of an elongated metal body as defined in claim 7, in which the quenching medium is discontinued upon further movement of said carriage and said heating means away from a surface portion under treatment.

9. Apparatus for heat treating in succession a plurality of spaced surface portions of an elongated metal body, some of such surface portions extending laterally from said body at different circumferential points, and other of said surface portions being cylindrical, such apparatus comprising, in combination, means for applying high temperature heat to such surface portions, said heating means being adapted normally to heat at any instant only a part of each surface portion longitudinally of said body; a support for said heating means comprising a carriage mounted upon and movable along a pivoted member, said carriage and said pivoted member being so constructed and arranged that said heating means is movable toward and away from said body and said pivoted member is caused to turn by movement of said carriage toward and away from said body; means pivoted on said carriage for registering the laterally extending portions of said body circumferentially of said body and in operative relation with respect to said heating means; means for engaging said carriage to position said heating means longitudinally of said body in positions corresponding to each of said surface portions to be treated; power means; means con-

nected with said power means for imparting a reciprocal motion to said carriage engaging means so as to reciprocate said heating means longitudinally of said body during heating; means adapted to rotate said body; means for selectively connecting said power means to said rotating means during the treatment of a cylindrical surface portion; means for directing a quenching medium against a heated surface portion; means for controlling the operation of said heating means; means for controlling the flow of quenching medium; and means associated with said pivoted member and so constructed and arranged that heating is discontinued and the quenching medium is turned on upon movement of said carriage and said heating means away from a surface portion under treatment.

10. Apparatus for heat treating in succession a plurality of spaced surface portions of an elongated metal body comprising, in combination, means for supporting said body; means for applying high temperature heat to such surface portions, said heating means being adapted normally to heat at any instant only a part of each surface portion longitudinally of said body; a support for said heating means comprising a carriage mounted upon and movable along a pivoted member, said carriage and said pivoted member being so constructed and arranged that said heating means is movable toward and away from said body and said pivoted member is caused to turn by movement of said carriage toward and away from said body; means for engaging said carriage to position said heating means longitudinally of said body in positions corresponding to each of said surface portions to be treated; power means; means connected with said power means for imparting a reciprocal motion to said carriage engaging means so as to reciprocate said heating means longitudinally of said body during heating; means for controlling the operation of said heating means; and means associated with said control means and pivoted member and so constructed and arranged that heating is discontinued upon movement of said carriage and said heating means away from a surface portion under treatment.

11. Apparatus for heat treating in succession a plurality of spaced surface portions of an elongated body comprising, in combination, means for supporting said body; means for applying high temperature heat to such surface portions, said heating means being adapted normally to heat at any instant only a part of each surface portion longitudinally of said body; a support for said heating means comprising a carriage mounted upon and movable along a pivoted member, said carriage and said pivoted member being so constructed and arranged that said heating means is movable toward and away from said body and said pivoted member is caused to turn by movement of said carriage toward and away from said body; means for engaging said carriage to position said heating means longitudinally of said body in positions corresponding to each of said surface portions to be treated; power means; means connected with said power means for imparting a reciprocal motion to said carriage engaging means so as to reciprocate said heating means longitudinally of said body during heating; means for directing a quenching medium against a heated surface portion; means for controlling the operation of said heating means; means for controlling the flow of quenching medium; and means associated with each of said

control means and said pivoted member and so constructed and arranged that heating is discontinued and the quenching medium is turned on upon movement of said carriage and said heating means away from a surface portion under treatment.

12. Apparatus for heat treating in succession a plurality of spaced surface portions of an elongated metal body, said surface portions extending laterally from said body at different circumferential points, such apparatus comprising, in combination, means for applying high temperature heat to such surface portions; a movable carriage for supporting said heating means, said carriage being movable longitudinally with respect to said body and also being movable toward

5 and away from said body; means pivoted on said carriage for registering a laterally extending portion of said body circumferentially of said body when said carriage is in a predetermined position away from said body, so as to place such registered portion in operative relation with respect to said heating means when said carriage is moved into another predetermined position closer to said body; means for engaging said carriage to position said heating means longitudinally of said body in positions corresponding to each of said surface portions to be treated; and means for imparting a reciprocal motion to said carriage engaging means so as to reciprocate said heating means longitudinally of said body.
